METHOD OF STABILIZING VOLATILE LIQUIDS

Paul D. Barton, Philadelphia, Pa., and Karl Finsterbusch, Scarsdale, and Nathaniel M. Floyd, Larchmont, N. Y., assignors, by mesne assignments, to American Locomotive Company, New York, N. Y., a corporation of New York

Application November 28, 1934, Serial No. 755,152

12 Claims. (Cl. 196—8)

Our invention relates to a stabilization and gas recovery process and more particularly to an improvement in the stabilization of crude petroleum, and pressure distillates and the recovery of stabilized light gasolines from these and refinery or natural gases.

Cracked gasoline, which is usually termed "pressure distillate", is generally separated, after condensation, from its attendant gases, at pressures varying from a few pounds per square inch gauge to 200 pounds per square inch or more. The condensate, which is generally termed "raw pressure distillate", contains hydrocarbon constituents, ranging from methane and other normally gaseous hydrocarbons to gasoline and heavier fractions depending upon the control of the temperature at the top of the fractionating tower of the cracking unit. The amount of the lighter components, such as methane, ethane and propane, the presence of which is not desired in the finished motor fuel product, is dependent on the pressure and temperature conditions of the separation. A practice sometimes resorted to in endeavoring to eliminate these components from the condensate, is to operate the separator at a relatively high temperature of approximately 130° F. and a low pressure of 2 or 3 pounds per square inch gauge. The elimination in such practice, however, is not complete and under these conditions relatively large amounts of desirable constituents such as butane, pentane, hexane, and some heavier hydrocarbons pass off with the rejected gases and must be recovered in order to provide for an efficient operation. Under higher pressures and lower temperatures the amount of desirable constituents which must be recovered from the rejected gases is, of course, less.

In practically all cases it is economical and desirable to fractionate the raw pressure distillate to eliminate propane and lighter fractions therefrom, so that the butane content will give the desired vapor pressure of the finished motor fuel. The raw pressure distillate, further, must be treated to remove sulphur compounds and other undesirable substances. The distribution of these compounds is usually such that concentrations are found between certain boiling ranges of the raw pressure distillate. It is, therefore, generally found expedient to fractionate the raw pressure distillate into various cuts containing these concentrations during the process of eliminating the propane and lighter fractions. The cuts may then be treated separately according to the sulphur compounds and the like present.

For example, a simple case is the fractionation of raw pressure distillate into three boiling range fluids, namely, propane and lighter, with butane in excess of that desired for vapor pressure requirements; butane, pentane, hexane and some heavier fractions; heptane and the heavier components. The first, or propane cut, is usually passed to fuel system. The second, or light gasoline cut, may be treated satisfactorily with a caustic wash. The third, or heavy gasoline cut, may be acid treated. It is sometimes of advantage to fractionate the heavy gasoline into two or more cuts depending upon the concentrations of detrimental compounds.

After treating and such other subsequent processing as may be necessary, the gasoline cuts are blended and mixed with "straight-run" gasoline to make the finished motor fuel. The separation of the light gasoline cut from the heavy gasoline eliminates excessive vaporization, treating, and rerunning losses which would otherwise prevail during the processing required by the heavy gasoline cut.

The fractionation of the raw pressure distillate is conventionally done by one of two methods. The first is to charge the raw pressure distillate to a high pressure fractionating tower from which the propane and lighter fractions are removed overhead. The heaviest fraction from this tower is passed to a second, lower pressure, tower, from which the light gasoline is recovered as an overhead or distillate product and the heavy gasoline as a bottom product. The heat required in this method is high because of the large quantity of reflux required in the high pressure tower and the high reboiling temperature necessary. Then, too, the high pressure tower is expensive since it must be relatively large to handle the total charge of raw pressure distillate.

In order to overcome these objections a second method is used in which the raw pressure distillate is charged to a low pressure tower from which the light gasoline, propane and lighter hydrocarbons are removed overhead, as a combined cut, and the heavy gasoline is removed from the bottom. The fractions removed overhead are condensed as completely as possible. Then the uncondensed vapors are passed to the refinery absorption plant or vapor recovery system for extraction of valued constituents, and the condensate is passed to a high pressure tower. The propane and lighter constituents are removed from this tower overhead and the light gasoline is withdrawn as a bottom product. The objection to the second method is the additional

processing to which the usually large volume of uncondensed vapors must be subjected.

It is desirable to recover a large light gasoline cut, since the treating requirements of this cut are the simplest and least expensive and for the advantages mentioned above with respect to the treating of the heavy gasoline cut. In order to accomplish this in the second method outlined, a deep cut (generally 20% or more of the raw pressure distillate) is made, leaving a heavy bottom product containing practically no hexanes and lighter constituents. The amount of condensation of the overhead cut, which also contains the normally gaseous components, is controlled by the available cooling water temperature and pressure obtainable in the condenser. The pressure is, in turn, partly dependent upon the heating medium available for reboiling the bottoms and in many instances upon temperature limitations due to the deleterious effect of high temperatures on the character of the bottoms. At the normally limited reboiling temperatures, only low pressures, relative to the pressures desired for condensation of the overhead without an unduly large portion remaining uncondensed, can be obtained because of the high boiling constituents in the bottoms. Under the relatively low condensing pressures, 20% to 60% of the overhead cut will generally remain uncondensed and pass off as wet gas. The recovery of valuable constituents from the wet gas is an added uneconomical step, particularly in view of the low pressure at which it is available.

It has been our experience that it has not been generally possible to effect substantially complete condensation of the overhead cut with the conventional system described above.

This difficulty may be overcome by removing from the raw pressure distillate prior to its introduction into the first, or low pressure, tower most of the undesirable light hydrocarbon constituents, methane and ethane, with a good portion of the propane. The absence of these removed, lighter fractions in the subsequent, overhead cut from the low pressure tower will permit complete or substantially complete condensation of this cut under temperature and pressure conditions readily obtainable in practically all installations.

Similarly, in high pressure absorption plants and/or absorption plants operated for high butane recovery from natural or refinery gases, methane, ethane and propane are absorbed along with the heavier fractions. These lighter fractions cause a difficult problem in the subsequent distillation and recovery of the gasoline components desired. Condensation of these components after distillation from the absorption medium is extremely difficult at the usual available temperatures of cooling water unless high pressures (80 to 200 pounds per square inch) are used. Naturally, high distillation pressures are disadvantageous from the standpoint of the consumption of stripping steam and general economical operation. The distillation pressures usually required are in excess of available steam pressure, condensation of distilled fractions is incomplete, vent gases are so rich as to require recompression or reabsorption, and the condensate has an excessively high vapor pressure, necessitating storage under pressure to prevent undue loss of gasoline prior to fractionation.

As we have pointed out in connection with the second method of fractionation of raw pressure distillate, these difficulties may be overcome if the absorbed methane, ethane and propane are

substantially eliminated prior to distillation. The gasoline fractions may then readily be completely condensed and recycling practically eliminated.

It is also to be noted that crude oils of low specific gravity contain relatively large percentages of low boiling gasoline and lighter fractions. Straight run gasolines from such crudes have a high vapor pressure, require stabilization and suffer undue vapor losses in their production. The process of our invention is particularly adapted to the stabilization of such crude oils and the simultaneous recovery of light gasoline from the natural gas present in the crude oil as it comes from the well. Thus it is to be observed that the character of the raw or inlet charging stock is not limited to low boiling hydrocarbons such as the pressure distillate and natural or refinery gases previously referred to.

It is an object of our invention to provide a process for recovering a stabilized gasoline from pressure distillate, natural or refinery gases, wherein the formation of wet gas requiring recycling or reprocessing is substantially eliminated.

It is a further object of our invention to provide a gasoline fractionating or recovery process in which the low boiling hydrocarbons which normally prevent complete condensation of the desired products at the temperature of the available cooling water are eliminated from the overhead products removed from the low pressure fractionating tower or still.

It is an object of our invention to provide a process for fractionating a distillate or long boiling range stock in which a high recovery of desired fractions at lower reboiling temperatures may be had.

It is another object of our invention to provide a process for recovering a stabilized gasoline and desired components from natural or refinery gases in which distillation with the use of lower distillation pressures may be employed.

It is an additional object of our process to provide an economical fractionation and/or absorption recovery in which utility requirements of heating, stripping, cooling and/or power are materially decreased.

It is a further object of our invention to provide a process for the separation of stocks into fractions prior to treating wherein treating is facilitated, losses minimized and a high recovery of desired fractions is effected.

Another object of our invention is to provide a combined absorption-fractionation process wherein the usual separate distillation step of conventional absorption recovery systems is eliminated.

A further object of our invention is to provide a process for stabilizing low specific gravity crude oils containing relatively large percentages of low boiling gasoline and lighter fractions.

Another object of our invention is to provide a combination absorption fractionation process for the recovery of gasoline fractions from natural gas and the removal of undesired low boiling fractions from crude oil.

Other and further objects of our invention will appear from the following description and the appended claims.

In the accompanying drawings which form part of the instant specification and are to be read in conjunction therewith and in which like numbers refer to like parts throughout the several views;

Figure 1 is a schematic showing of one form of refinery or natural gas absorption stabilization

system capable of carrying out the process of our invention.

Figure 2 is a schematic showing of one form of pressure distillate stabilization system capable 5 of carrying out the process of our invention.

Figure 3 is a schematic showing of one form of a combination absorption-fractionation system capable of carrying out the process of our invention.

10 In general, we have provided a process by which the large volume of uncondensed wet gas incident to refinery absorption and fractionation systems are greatly diminished, with resultant economies of operation due to elimination of the usual recycling or reabsorption operations and reduction in reboiling temperatures or distillation pressures.

We have accomplished this by eliminating, from the feed to the usual low pressure fractionator of the fractionation system or to the combined still and rectifier of the absorption system, those 20 very light gaseous hydrocarbons which are normally uncondensable at the temperature of the available cooling water and the relatively low 25 pressure existing in the low pressure tower. Such hydrocarbons are predominantly methane and ethane either alone, together, or admixed with propane and minor quantities of butane and heavier hydrocarbons. As a result of the elimination 30 of the greater proportion of these light constituents, the gases and vapors taken off overhead from the low pressure tower may be substantially completely condensed, or, as in the stabilization of crude oil, the percentage of uncondensed overhead products may be greatly decreased to provide the raw charging material for the high pressure fractionating tower, as well as reflux for the low pressure tower and the flash tower used to remove the lightest hydrocarbons. 35 The light hydrocarbons removed from the material being passed to the low pressure tower, are subjected to fractionation with the charge to the high pressure fractionator when maximum gasoline recovery is desired. A condensate from the 40 gaseous overhead products from the high pressure tower is returned thereto as reflux. The heaviest fraction of reflux condensate from the low pressure tower of the fractionation system is stabilized 45 pressure distillate of low vapor pressure, ready for delivery to a treating step. The heaviest fractions from the low pressure towers in the absorption systems are the lean oils from which the natural or refinery gases have been distilled. The heaviest fraction of reflux condensate from 50 the high pressure fractionating tower in the fractionation and absorption systems, is a stable light gasoline of desired vapor pressure specifications for use as produced, or for blending with heavier gasoline for motor fuel.

More particularly referring now to Figure 1, we have disclosed an absorption system for the recovery of stabilized light gasoline from natural, refinery, or gases from any suitable source, by the process of our invention. A gaseous mixture from 60 the selected source containing methane and ethane and heavier hydrocarbons is fed through the line 1 to the bottom of an absorption tower 2 in which it rises upwardly and comes into intimate contact with a suitable absorption oil flowing down the tower. Those gases which are not absorbed by the oil pass off overhead through the residue gas line 3. The rich oil is withdrawn by means of a line 4 having a pump 5 and passes at relatively high pressure through a plurality of 65 heat exchangers 6 in heat exchange relationship

with hot lean oil returning to the absorption tower. The oil is further heated by passing through a heater 7 which is supplied with heating fluid through a line 8 and removed through a line 9. The hot oil is delivered through the line 4a 5 and valve 4b to a flash distillation tower 10, the pressure being controlled therein by valve 11a at from 150 to 300 pounds per square inch, for example. This pressure and the flash tower temperature is so controlled as to cause most of the 10 methane, ethane and propane, together with smaller amounts of butane and heavier hydrocarbons to be volatilized from the rich oil and delivered as an overhead cut, together with vaporized reflux from the flash tower, through the line 15 11. The characteristics of this cut may be controlled by means of the fractionating trays 12 and reflux which is introduced at the top of the tower by means of the line 13 controlled by the valve 13a. The flash tower 10 is provided with a plurality of baffles 12.

The liquid product which accumulates in the base of the flash tower and which now contains but a trace of methane and ethane is caused to flow through the line 14 and the valve 14' to a 25 selected one of a number of trays 15 located in a low pressure combined still and rectifier 16. It is to be understood that any desired number of trays may be provided within the tower 16 for controlling the characteristics of the products 30 to be removed from this tower and particularly for preventing the passage of absorption oil vapors into the overhead products. This tower is, for example, normally maintained at a pressure relatively lower than that in the flash tower 35 10, for example, a tower pressure of from about 20 to 100 pounds per square inch, thus enabling liquid to flow between the towers as the result of pressure differential. Steam is admitted, below the lowest tray, through the line 17 and/or, 40 in some cases it is desirable and feasible to supply reboil heat at the base or still portion of the tower for vaporization of the absorbed hydrocarbons instead of introducing direct steam. The reboil heating medium may be supplied through pipe 17a to coil 18 within the tower 16 passing out through line 19. Direct steam released within the tower will serve to strip, from the absorption oil, the remaining absorbed hydrocarbons which, together with vaporized reflux, are taken off overhead through the line 20, the vapors being partially condensed by means of the reflux condenser 21, and delivered therefrom through the line 22 to a gasoline reflux accumulator 23. This gasoline condensate is pumped through a line 24 having a pump 25 to a suitable point in the rectifying portion of the tower 16 for use as reflux to ensure that absorption oil vapors are knocked back in the tower. When direct steam is used for stripping and the top temperature of tower 16 is such that under its operating pressure some steam will condense, this steam condensate may be separated from the liquid gasoline and withdrawn from tower 16 by line 24a. Steam not condensed in tower 16 is condensed in reflux condenser 21, separated from the reflux in accumulator 23 and withdrawn therefrom by line 24a. The uncondensed vapors (overhead products) from the accumulator 23 pass through the line 26 to a final condenser 27 where substantially 70 complete condensation of the products stripped from the oil is effected at the temperature of the available cooling medium and at the pressure existing in the combined still and rectifier 16. The condensate from the vapor condenser 27 is de- 75

livered through the line 28 to an accumulator 29. Those vapors which are uncondensed, the quantity of which will be comparatively negligible in accordance with the desired objects of our invention, will pass off through the lines 30 and 31' to a fuel gas system or to a gas recovery system. The pressure on combined still and rectifier 16 is controlled by valve 26a or valve 30a which controls the pressure on accumulator 29.

10 The stripped lean oil from the bottom of the low pressure combined still and rectifier 16 is passed through the line 62 and heat exchangers 6 to the coolers 63 having cooling liquid inlet and outlet lines 65 and 66 respectively. The cooled 15 lean oil is delivered through the line 66 to lean oil surge tank 67 from which it is pumped through a line 68 by pump 69 to the upper part of the absorption tower 2.

The raw unstable gasoline which is collected in 20 the accumulator 29 is delivered through the line 31 by a pump 32 to the branch lines 13 and 33. A small percentage of this raw feed is delivered, as previously pointed out, through the line 13 to the flash tower 10 for reflux purposes. The 25 remainder of the raw feed is pumped through the line 33 and heat exchangers 34, to a header 35 from which a plurality of valved feed lines 36, 37 and 38 lead the raw gasoline to respective trays 39 in the high pressure fractionator 40. At 30 the same time, the overhead cut and vaporized reflux from the flash tower 10 passes through the line 11 to a header 41 from which one or all of valved feed lines 42, 43, and 44 lead the vapors and gases to the trays 39 in the tower 40. Thus 35 all or practically all of the absorbed constituents are delivered to the high pressure fractionator without the necessity of recycling relatively large volumes of wet gas consisting of constituents originally absorbed. At the higher fractionation 40 pressures of from 150 to 300 pounds per square inch, for example, existing within this tower, the overhead products will consist mainly of methane, ethane and propane with a controlled amount of butane, which pass through the line 45 to the reflux condenser 46. The resultant condensate (reflux) and uncondensed vapors are delivered through the line 47 to reflux accumulator 48 from which reflux is returned by means of a line 49 by a pump 50 to the upper portion of 50 the fractionating tower 40. Those gases (overhead products) uncondensed by the vapor condenser 46 are delivered through the lines 51 and 51' to a fuel gas system. The pressure of fractionator 40 is controlled by valve 51a.

55 The bottoms of the fractionator 40 are delivered through a line 52 to a reboiler 53 to which steam or other heating medium is supplied by means of a line 54 and removed by a line 55. The vapors evolved in the reboiler 53 are returned to 60 the fractionator through the line 56, the liquid products passing through line 57 and heat exchangers 34 where a certain amount of the heat content is abstracted by the raw feed being delivered to the fractionator 40. The partially 65 cooled fractionated product in line 57 is delivered to the cooler 58 which is provided with cooling liquid inlet and outlet means 59 and 60 respectively. The relatively cool stabilized light gasoline may be delivered through the line 61 to 70 storage.

75 Referring now more particularly to Figure 2, we have disclosed a system for fractionating raw pressure distillate and for recovering a stabilized light gasoline in which the pressure distillate is fed through a line 1a to a pressure feed tank 2a

from which the residue gas leaves through the line 2b and valve 2c. The distillate is withdrawn from this tank through a line 4, by pump 5 and passed through the heat exchanger 6, heater 7, line 4a and valve 4b to the flash distillation tower 10 equipped with a plurality of fractionating trays 12 and baffles 12'. This tower is operated at pressures, for example, between 150 to 300 pounds per square inch and will serve to remove from the distillate, as an overhead product comprising 10 the major portion of the light hydrocarbon gases, methane, ethane and propane, with small amounts of butane and heavier hydrocarbons which are delivered with the vaporized reflux through the line 11 and valve 11a to a high pressure 15 fractionator 40 as will be more fully pointed out hereinafter. The unvaporized products in the tower are delivered through the line 14 controlled by a valve 14' to a header 14a from which a plurality of valved feed lines 14b, 14c, and 14d 20 lead respectively to the trays 15b, 15c, 15d in a low pressure fractionating tower 16. It is to be understood, of course, that any suitable number of trays necessary to accomplish the desired fractionation may be provided in the tower 16, which 25 may be provided with stripping steam inlet 17a. The pressure in this tower will normally vary between 20 and 100 pounds per square inch, for example, depending upon the specifications desired in the bottom products. The overhead 30 product from this tower will be substantially devoid of methane and ethane and, together with vaporized reflux, is removed through the line 20 and passed to the reflux condenser 21. Reflux condensate is delivered from the condenser 21 by 35 means of a line 22 to a reflux accumulator 23 from which reflux is delivered by means of a line 24 by pump 25 to the upper part of the fractionator 16 for end point temperature control of the evolved vapors. The remaining uncondensed vapors, 40 which are the overhead product, pass through the line 26 to the final condenser 27 where complete or substantially complete condensation of the vapors at the temperature of the available cooling water and the pressure existing in the fractionator 16 is effected. The raw unstable light gasoline is then delivered by means of the line 28 to an accumulator 29, the relatively negligible amount of uncondensed vapors, if any, passing off through the lines 30 and 31' to a fuel gas system 50 or, if desired, to a recovery system. The pressure on the fractionator 16 is controlled by valve 26a or by valve 30a which controls the pressure on the accumulator 30.

The raw gasoline from the accumulator 29 is 55 delivered through the line 31 by a pump 32 to the branch lines 13 and 33. A small proportion of this raw gasoline is delivered through the branch line 13 and valve 13a to the upper part of the flash tower 10 for reflux purposes. The remainder of 60 the raw feed passes through branch line 33 and valve 33a and heat exchangers 34 to a header 35 having a plurality of valved feed lines 36, 37, and 38, connected to trays 39 in a high pressure fractionator 40. Any suitable number of trays may, 65 of course, be provided in this tower.

The overhead cut and vaporized reflux from the flash tower 10 is delivered by means of the line 11 and valve 11a to a header 41 having a plurality of valved feed lines 42, 43 and 44 leading to the 70 trays 39 and the tower 40. Thus all light gasoline constituents are sent to the high pressure fractionator and there is no recycle. It is possible by suitable manipulation of these valves to deliver the feed to the high pressure fractionator to any 75

- selected tray of the group. The overhead product and vaporized reflux in the tower 40 are removed through the line 45 and delivered to a vapor condenser 46 from which the condensate formed flows through the line 47 to a reflux accumulator 48. The liquid collected in this accumulator is returned through a line 49 by pump 50 to the upper part of the tower 40 as reflux. The uncondensed vapors and gases (overhead product) in the accumulator 48 pass off through the lines 51 and 51' and valve 51'a to the fuel gas system. The overhead cut from the tower 40 will normally be mainly methane, ethane, and propane with a controlled amount of butane.
- 15 The bottom product in the tower 40 is delivered by means of the line 52 to a reboiler 53 to which steam or other suitable heating medium is supplied through line 54 and removed through line 55. Vapors evolved in the reboiler are returned 20 to the tower 40 through the line 56, the final fractionated product being withdrawn through the line 57, passed through the heat exchangers 34 and then delivered to coolers 58 having cooling water inlet and outlet means 59 and 60 respectively. The cooled stabilized light gasoline containing the desired amount of butane for vapor pressure specifications is then delivered to storage through the line 51.
- 25 The liquid bottoms in the low pressure fractionator 16 are delivered by a line 52a to a reboiler 62b to which suitable heating medium is supplied through a line 17 and removed through a line 19. The vapors evolved in the reboiler are returned to the tower through the line 62c, the unvaporized liquid, which is the stable pressure distillate, being delivered by the line 62 through the heat exchangers 6 and coolers 63 having cooling liquid inlet and outlet lines 64 and 65 respectively. The cooled distillate leaves the coolers 63 through the line 66 and is led to a treating plant (not shown).
- 30 The above illustrations of the application of our process consider butanes as the lowest boiling fraction desired in the recovered products. It is to be understood that the application is not limited in this respect. Constituents boiling lower or higher than butane may readily be recovered as the lowest boiling fraction in the finished products by suitable adjustment of temperatures and pressures. It is also understood that the number of products and points of separation are not limited to those illustrated. The bottom products from the low and high pressure fractionators may be further separated into additional products in additional fractionating towers not shown. The 35 overhead product from the high pressure fractionators may be totally or partially condensed and the condensate fractionated into additional products. These and other combinations are within the scope of our process.
- 40 Referring now to Figure 3, we have disclosed a combination absorption fractionating system for the recovery of gasoline fractions from natural gas and removal of undesired low boiling fractions from crude oil.
- 45 Crude oil containing natural gas as it comes from the well, enters through the line 1a into the usual field separators 2a, one of which is shown, where the gas is separated and passed through the line 2b and valve 2c to an absorber 2 where an absorption medium, in this case stabilized crude oil introduced through line 68 and valve 68a, extracts the gasoline components from the gas.
- 50 The volatile, unstable crude oil leaves the separator 2a through the line 2d and valve 2e and is pumped by pump 2f into the line 4 where it is joined by and admixed with the rich absorption oil pumped by the pump 5 from the absorber through the line 4. The mixture passes through heat exchangers 6 where it is heated by the hot stable crude oil flowing through the line 62 and, if desired, is further heated in a preheater 7 having heating liquid inlet and outlet lines 8 and 9 respectively before passing through line 4a and valve 4b to the flash distillation tower 10.
- 55 The temperature of the mixture and pressure of the flash tower 10 are so regulated that a large portion of the propane and lighter constituents, together with some butanes and heavier, contained in the mixed feed are vaporized. End point temperature control of overhead vapors is generally not of great importance but may readily be regulated by use of reflux and rectifying plates 12 above the flash section.
- 60 The bottoms from the flash tower pass through the line 14 to a header 14a having the valved branch lines 14b, 14c and 14d connected respectively to the trays 15b, 15c and 15d of the crude oil fractionating tower 16 where propane and lighter fractions, together with practically all of the butane and lesser amounts of pentane and heavier, are taken overhead. Vaporized reflux, which is a condensate approaching substantial equilibrium with the overhead cut, also passes overhead. The total vapors leave the tower 16 through the line 20 and pass through a reflux condenser 21 and line 22 into an accumulator 23 from which reflux is pumped back to the tower through a line 24 by means of a pump 25. The uncondensed gases (overhead cut) pass through line 26 and valve 26a to a final condenser 27 and thence through line 28 to an accumulator 29. In most cases complete condensation of the overhead cut cannot be obtained at the condensing temperature and pressure available. However, the absence of light fractions eliminated in the flash tower greatly increases the amount condensed. Uncondensed vapors may be sent through line 74 and valve 75 to fuel gas main 71 or, if at a pressure greater than that on the main absorber 2, returned to this absorber through line 30, valve 31a, recycle line 69' and valve 73 for extraction of gasoline constituents. If their pressure is below that of the main absorber a separate reabsorber (not shown) may be used to process these vapors.
- 65 The bottoms of the crude fractionator leave through line 62a, valve 62b, and are pumped by pump 62c through a convection heated coil 62d and radiant heated coil 62e for reboiling in a furnace heater 62f which may be fired by residue dry gas or other suitable means by means of burners 117 and 118. A furnace is generally desirable in order to effect a high reboiling temperature (400°-600° F.) for example, at the base 70 of the column and in turn develop as high a pressure as practicable. The higher this pressure, of course, the more complete the condensation of the overhead cut will be as previously pointed out.
- 75 The bottom product of the crude oil fractionator leaves through the line 62 and passes in countercurrent heat exchange with the mixed feed in exchangers 6 and then passes through the coolers 63 having cooling liquid inlet and outlet means 64 and 65 respectively. The cooled oil leaves through the line 66, a portion of the cooled stable crude oil passing through valve 66d and line 66c being withdrawn for use as absorption medium. This oil is delivered to the 75

surge tank 67 from which it leaves through line 68 and is pumped by pump 69 through valve 68a into absorption tower 2. Small amounts of pentane and heavier fractions still remaining in the 5 stable crude oil used as absorption medium will be vaporized and pass off with the residue gas through the line 3 and valve 3a to the residue gas main 71. The quantity of gasoline constituents lost in this manner, however, will be far 10 less than the amount absorbed from the wet gas and the net gain makes this step advantageous. If desired, a portion of the stable crude oil may be further fractionated, in towers not shown, to obtain a more suitable absorption medium and 15 thus eliminate the losses to the absorber residus gas. In this case the rich oil may be processed in a conventional distillation unit or as already described.

20 The condensate collected in the final accumulator 29 is pumped by pump 32 from the line 31 through valve 33a and line 33 to join and be mixed in line 11' with the overhead products and vaporized reflux leaving the flash tower through the line 11. A portion of the condensate 25 is returned through line 13 and valve 13a to be used as reflux for the flash tower 10. The mixed condensate and flash tower vapors pass through the line 11' to a condenser 33b having cooling liquid inlet and outlet lines 33b' and 33b" respectively and thence through line 33c to accumulator 33d which is held at a pressure somewhat below the flash tower pressure. In this 30 manner the major portion of absorbed gasoline fractions and components fractionated from the inlet crude oil are subjected to condensation at a pressure much higher than could readily and practicably be obtained by reboiling the stable crude.

35 Uncondensed gases and vapors leave this 40 accumulator through line 67' and valve 68' but will be relatively small in amount and may be sent to the residue gas main 71 through valve 72 or returned to the main absorber 2 through line 69' and valve 70 or processed in a high pressure reabsorber not shown.

45 If reabsorbers are used, rich oil therefrom may be processed similar to the rich oil from the main absorber.

50 If desired, the flashed vapors and crude fractionator overhead condensate may be sent directly to the high pressure fractionator 40 as is shown in Figures 1 and 2.

55 In Figure 3, the high pressure accumulator 33d serves as a feed tank for the high pressure fractionator 40. The condensate accumulated in the feed tank leaves through the line 33e and valve 33f and is pumped by pump 33g through line 33h and heat exchangers 34 to a header 35 from which the valved branch lines 36, 37 and 38 lead to 60 selected trays 39 of the high pressure fractionator 40.

65 Propane and lighter constituents together with some butane if desired, are cut overhead, and together with vaporized reflux, leave through the line 45, pass through the reflux condenser 46 having cooling liquid inlet and outlet lines 46' and 46" respectively, the condensate then passing through the line 47 to reflux accumulator 48. Reflux is returned to the tower 40 through the line 49 by 70 the pump 50. The uncondensed gases (overhead cut) will be permitted to escape through the line 51 and valve 51a of the reflux accumulator 48.

75 The bottom product of the fractionator 40 will consist mainly of butane and heavier fractions. This product passes from the fractionator to a

reboiler 53 through a line 52. Steam or other heating medium is admitted to the reboiler through the line 54 and is removed through the line 55. The vapors evolved are returned to the fractionator 40 through the line 56. The unvaporized bottoms in the reboiler leave through the line 57, pass through the heat exchangers 34 and coolers 58, the latter having cooling liquid inlet and outlet lines 59 and 60 respectively, being finally removed as stable light gasoline through 10 the line 61.

If desired, this light gasoline bottom product may be blended with the stable crude and the mixture sent to the refinery. The straight run gasoline produced from this crude will be stable since 15 propane and lighter fractions are not present.

20 In the processing of a low specific gravity crude in the apparatus arrangement of Figure 3, the oil may issue from the well at a rock pressure of, say 20 for example, 75 pounds per square inch. In such a case, the absorber 2 would be operated at a pressure of from 65-70 pounds per square inch, the flash distillation tower 10 at a pressure of 200 pounds per square inch, and at a temperature of 25 about 500° F., the primary low pressure fractionator at a pressure of about 80 pounds per square inch with the reboiling temperature of the bottoms about 550° F. and with the primary final condenser 27 and accumulator 29 at a pressure of 30 about 75 pounds per square inch to permit the return of the uncondensed gases to the absorber if it is so desired. The high pressure fractionator 40 operates at a pressure of about 265 pounds per square inch with the reboiling temperature of the bottoms around 345° F. The vapor condenser 33b 35 and accumulator feed tank 33d interposed between the flash tower 10 and high pressure fractionator 40 operate at a pressure of about 185 pounds per square inch.

40 The recital of pressures and temperatures is not to be considered as limitative and should be construed as by way of example only, since it will be obvious to one skilled in the art that the operating pressures and temperatures will be determined by the character of the material being processed and 45 the specifications desired in the products resulting therefrom.

45 It will be seen from the above description that our process may be used to stabilize crude oils and at the same time extract natural gasoline from 50 natural gas. The extraction step, however, is not necessary in the accomplishment of the crude stabilization step.

55 It will be observed that we have accomplished the objects of our invention and provided a process by which large volumes of uncondensed wet gas usually incident to refinery absorption and fractionation systems are greatly diminished or eliminated with resultant economies of operation due to elimination of the usual recycling or reabsorption operations.

60 It is also evident that our process has a wide range of application and it is understood that we are not limited to those described. Additional steps may be added to the process without departing from the spirit of the invention as defined by the appended claims. Cold vents, additional flashes, absorptions, fractionations, and/or distillations may be incorporated in various combinations and sub-combinations.

65 It will be understood that certain features and sub-combinations are of utility and may be employed without reference to other features and sub-combinations. This is contemplated by and 70 is within the scope of our claims. It is further 75

obvious that various changes may be made in details within the scope of our claims without departing from the spirit of our invention. It is, therefore, to be understood that our invention is not to be limited to the specific details shown and described.

Having thus described our invention, what we claim is:

1. A process for recovering a stable light gasoline from a raw pressure distillate comprising flashing the distillate to remove substantially all hydrocarbons having less than three carbon atoms per molecule, fractionating the balance of the distillate at a lower pressure, removing from the fractionation zone a liquid fraction composed mainly of hydrocarbons having more than five carbon atoms per molecule, separately removing from the fractionation zone vapors composed mainly of hydrocarbons having more than two and less than seven carbon atoms per molecule, substantially completely condensing the vapors, fractionating the condensate and the vapors from the flash zone in a second fractionating zone of higher pressure, removing from the second fractionating zone hydrocarbon vapors having mainly less than four carbon atoms per molecule and separately removing from the second fractionation zone a stable light gasoline composed of hydrocarbons having mainly more than three carbon atoms per molecule.

2. A process for stabilizing crude hydrocarbon oils containing relatively large percentages of low boiling gasoline and lighter gas fractions, comprising separating the crude oil into a first distillate vapor fraction and a crude oil residue, subjecting the crude oil residue to a fractionating operation at a lower pressure and removing as products thereof a second distillate vapor fraction and a stabilized crude oil, said second distillate vapor fraction being by reason of said separating operation substantially completely condensable at a pressure no higher than that at which said fractionating operation is conducted and at normal atmospheric temperature, condensing the second distillate vapor fraction, fractionating the vapor condensate with the first distillate vapor fraction at a higher pressure than that at which said first fractionating operation is conducted and removing a stable light motor fuel as a product of the last mentioned fractionating operation.

3. An absorption-fractionation process for stabilizing crude hydrocarbon oil and simultaneously recovering a stabilized motor fuel from natural gas in the oil comprising separating wet gas from the crude oil, subjecting the wet gas to an absorption operation with a lean absorption oil, subjecting the rich oil resulting from the absorption operation together with the crude oil from which the wet gas was separated to vaporizing conditions of temperature and pressure sufficient to vaporize relatively low boiling hydrocarbons of the combined oils, separating the oil vapors formed from the resulting liquid residue, subjecting the liquid residue resulting from the vaporizing operation to a fractionating operation, recovering as products of the fractionating operation a stabilized crude oil and distillate vapors, said distillate vapors being by reason of said initial separating operation substantially completely condensable under a pressure no higher than that at which said fractionating operation is conducted and at normal atmospheric temperature, cooling the distillate vapors to substantially completely condense said vapors and thereby form a vapor condensate, admixing said condensate with the first mentioned oil va-

pors, cooling the mixture to form a second condensate, subjecting the last mentioned condensate to a fractionating operation at a pressure greater than that in the first fractionating operation and recovering as a product of said last mentioned fractionating operation a stabilized motor fuel.

4. The process of claim 3 in which a portion of the stabilized crude oil from the first fractionating operation is passed in an elongated confined stream a heating zone and returned to the fractionating operation.

5. A process for recovering a desired liquid hydrocarbon product from refinery or natural gas comprising absorbing constituents of the gas including constituents which are to form the desired product in an absorption oil, flashing the lightest absorbed constituents from the oil, separately and at a reduced pressure distilling the remaining heavier absorbed constituents from the oil, fractionating the distilled constituents to recover vapors free of absorption oil, condensing the vapors, fractionating resultant condensate at a higher pressure with the constituents flashed from the absorption oil and recovering the desired hydrocarbon liquid product as a product of the last named fractionating operation.

6. The process of claim 3 in which a portion of the vapor condensate condensed from distillate vapor products of the first fractionating operation is employed as reflux in the vaporizing operation and in the first fractionating operation for end point temperature control of oil vapors produced in said vaporizing operation and said first fractionating operation.

7. The process of claim 3 including the step of employing stabilized crude oil recovered as a product of the first mentioned fractionating operation as lean oil in the absorption operation.

8. In a process wherein a hydrocarbon mixture including gasoline-like hydrocarbons is fractionated in a first fractionating zone to separate the heavier from the lighter hydrocarbons of the mixture, and wherein certain of said lighter hydrocarbons are then fractionated in a higher pressure fractionating zone to recover a stabilized light motor fuel; the improvements comprising removing such a portion of the lighter hydrocarbons from the mixture before the first fractionating step is performed that hydrocarbons uncondensed by the first fractionating operation are substantially completely condensable under a pressure no higher than exists in said first fractionating zone and at normal atmospheric temperature, then performing said first fractionating operation on the balance only of said mixture, and, subjecting the initially removed portion of lighter hydrocarbons to fractionation in the higher pressure fractionating zone with the lighter hydrocarbons from the first fractionating zone.

9. A process for obtaining a stabilized light liquid product of desired vapor pressure from a liquid having a higher vapor pressure comprising heating the liquid at a pressure substantially above atmospheric, causing the heated liquid to be flashed into a first vapor fraction and a first liquid fraction each having a vapor pressure higher than that of the desired product, fractionating only the first liquid fraction and recovering as products of the fractionating operation a second vapor fraction of higher vapor pressure than that of the desired product and a second liquid fraction of lower vapor pressure than that of the desired product, said second vapor fraction being by reason of said flashing operation substantially completely condensable at a normal temperature under

- substantially the pressure at which said fractionating operation is carried out, continuously removing the second liquid fraction from the process, substantially completely condensing the second vapor fraction without increasing the pressure thereon, subjecting condensate resulting to fractionation at a higher pressure, subjecting the first vapor fraction to the higher pressure fractionation with condensate obtained from the second vapor fraction, and recovering as a product of the last named fractionating operation the stabilized light liquid product of desired vapor pressure.
10. A process for recovering a narrow boiling range hydrocarbon fraction from a hydrocarbon fraction of relatively wider boiling range comprising introducing the hydrocarbon fraction of relatively wider boiling range as a liquid under pressure into a flash zone wherein it is flashed under reduced pressure to thereby create under the temperature and pressure conditions therein a first liquid residue and a first vapor fraction, separately removing the fractions from said flash zone, subjecting only the residue liquid of the flashing operation to fractionation in a fractionation zone 20 of lower pressure than the flash zone to secure a second liquid residue and a second vapor fraction, said second vapor fraction being by reason of said flashing operation substantially completely condensable at the pressure existing in the fractionating zone and at normal atmospheric temperature, substantially completely condensing the second vapor fraction, returning a portion of the condensate from the second vapor fraction to the flash zone as reflux, subjecting a major portion of the condensate to fractionation in the second fractionating zone of relatively higher pressure than that in the first fractionating zone, introducing the first vapor fraction into the second fractionating zone, separately removing the uncondensed vapors and the desired narrow boiling range hydrocarbon fraction from the second frac-

tionating zone, condensing vapors removed from the second fractionating zone and returning resultant condensate formed to the second fractionating zone as reflux.

11. In a process wherein a hydrocarbon liquid comprising normally liquid and normally gaseous hydrocarbons is operated on under a relatively low pressure in a primary stabilizing zone to obtain a stabilized heavy liquid fraction and a relatively light fraction comprising the more volatile hydrocarbons and wherein said light fraction is thereafter cooled and resultant condensate operated on under a relatively high pressure in a secondary stabilizing zone to obtain a stabilized light liquid fraction; the improvement comprising the steps of flashing said liquid prior to said primary stabilizing operation under conditions of temperature and pressure effective to free said liquid of such a portion of its excessively volatile constituents that the light fraction when obtained as aforesaid will be substantially completely condensable when cooled under a pressure no higher than that pressure under which said primary stabilizing operation is conducted, with cooling liquid at a normal temperature, carrying out said flashing operation under a pressure higher than that pressure under which said secondary stabilizing operation is carried out and operating on the portion freed from said liquid by said flashing operation in said secondary stabilizing zone to recover therefrom desired constituents thereof as a part of said stabilized light liquid fraction.

12. The process of claim 5 wherein the distillation operation is carried out at a temperature and pressure such as will permit substantially complete condensation of the distilled vapors at the temperature of the available cooling water.
